Specification of Letters Patent.

Patented Feb. 8, 1916.

Application filed February 11, 1913. Serial No. 747,653.

To all whom it may concern:

Be it known that we, WILLIAM F. STRAUB and ALBERT A. RADTKE, citizens of the United States, residing at Chicago, in the county of Cook and State of Illinois, have invented a certain new and useful Improvement in Motors, of which the following is a full, clear, concise, and exact description, reference being had to the accompanying drawings, forming a part of this specification.

Our invention relates to motors and has for its object the provision of improved means for receiving and indicating time, our invention being more particularly related to what we might call secondary clocks or such as are under the control of a master clock.

Our invention concerns itself with that character of system for sending and indicating time which in its general nature may be said to be similar to that disclosed in the patent to A. A. Radtke, No. 921,280, issued May 11, 1909.

The improved secondary clock which forms the subject matter of this application is designed to receive certain impulses of current in a certain order, which impulses are controlled by a master clock, and which impulses suitably actuate the secondary clock to thereby indicate the time as given by the master clock.

In one form of carrying out our invention, we have three magnets symmetrically arranged about an axis, which magnets control an armature, which armature is so arranged that succeeding energizations in rotation of said magnets cause rotation of said armature, thereby to actuate suitable hands to indicate the time. We prefer to employ a single armature for the electromagnets, although of course, our invention is not to be so limited, and this armature preferably has a plurality of radial elements so arranged that one of these elements is nearest to that particular idle magnet which is next to be energized. In this way it will be seen that the armature may rotate as these magnets are successively engaged.

Our invention contemplates a preferred form for this armature construction.

Our invention also contemplates means whereby in a device of this general char-

acter suitable locking or holding mechanism is provided which may hold the armature in a certain position pending subsequent energization of another electromagnet, and which devices at the same time are applicable to bring the armature to the exact position it is supposed to occupy for each particular energization. In this way we avoid any difficulty that there may be of the armature being retracted or prevented from following to its peculiar resting positions as designated, but at all times have this armature occupy the particular position as predetermined from the particular energization of the electromagnets as outlined.

We will describe our invention more in detail by referring to the accompanying drawings illustrating the same in which—

Figure 1 is a side view partly in section of our improved secondary clock; Fig. 2 is a sectional view on line *a—a* of Fig. 1; Fig. 3 is a detail view of the auxiliary armature controlling mechanism, a portion of the armature being shown as removed more clearly to reveal the structural details; Fig. 4 is a detail view of the binding post mechanism, and Fig. 5 is a diagrammatic view to illustrate the inter-relation between the master and secondary clocks.

Referring more particularly to Fig. 1, we show a casing 1 preferably having a cover 2 provided with a crystal 3 and having a wall 4 to make a hand compartment within which suitable hands 5 and 6 for time indicating purposes are mounted concentrically with the shaft 7. The hands are both driven through the agency of intermediate gear wheels 8 and 9 as will be well understood to indicate hours and minutes, the gear wheels receiving their rotative effort from an armature 10. This armature is fastened to a shaft 11, which shaft is pivoted on the bearing 12, and which also carries at its lower extremity a second armature 13. The upper end of this shaft is provided with suitable sleeves as may be required to accommodate the hands, and is also guided by the bracket 14 held in place upon suitable studs secured to a plate 15. The plate 15 in connection with a second plate 16 hold between them three electromagnets 17, 18 and 19. The plate 16 also

has studs 20 to hold the bridge 21 which carries the bearing stud 12. The structure comprising the three electromagnets together with plates 15 and 16, and which structure carries the armature shaft together with the armatures, is held in the cover 1 in any suitable manner. The plates 15 and 16 together with the electromagnets being engaged within the casing 1, the armatures 10 and 13 together with their shaft, however being permitted to rotate in response to energizations of the electromagnets, thereby to drive the hands 5 and 6 to indicate the time.

As will be more clearly apparent from Fig. 2, the armatures 10 and 13 have apertures punched therein which leave the armature with a plurality of radial elements 22 throughout its entire periphery, which elements are the particular ones adapted to operate with the cores 23, 24 and 25 of the electromagnets 17, 18 and 19 respectively. These cores project through the electromagnets a slight distance, of course, so that these cores are adapted to coöperate simultaneously with both armatures 10 and 13. Referring to Fig. 2, it will be seen that the element 22 which is immediately over the core 25 is the one that has been last called upon to perform its function of rotating the armature, electromagnet 19 being the one to be last energized. The next electromagnet to be energized will be 18 and a coöperating element 22 of this magnet is in such close proximity that it will move directly over the center line of this electromagnet 18 when it is energized. Thereby the armatures are moved clockwise a slight angular distance sufficient to bring the element 22^a into such proximity to the core of the electromagnet 17 that the next energization of the electromagnet 17 will cause attraction of this element 22^a to thereby further move the armatures in a clockwise direction of rotation, and thus the series of energizations of these electromagnets continues to thereby cause intermediate rotation of the armature in answer to movements of the master clock, thus to indicate the time by means of the hands 5 and 6. The armature 10 is provided with a plurality of pins 26, there being one pin for each radial element 22, and these pins coöperate with suitable devices more clearly shown in Fig. 3 to so control the movement of the armature that its movement in answer to each impulse will bring the armature exactly into the position where its operative element 22 is directly centered with respect to the electromagnet. These devices also cause suitable holding of the armature until the energization of the following electromagnet takes place, at which time the particular device last employed releases the armature, and permits the device of the next succeed-

ing electromagnet to come into play. In Fig. 3 we have shown these devices and have shown the pins 26 of the armature 10, the armature 10 having been omitted from this illustration more clearly to reveal the operation of these devices now to be explained. These devices preferably consist of pivotally mounted arms 27 pivotally mounted at 28 in the plate 15, which elements 27 are of magnetic material and have pole pieces 29 adapted to be controlled by the particular electromagnet with which they are associated. The elements 27 also carry cams 30, which cams are adapted to enter between adjacent teeth 26, thereby to accurately center the armature upon each energization of the electromagnet. Assume for instance that the electromagnet 19 has been energized to cause the armature to occupy such position which would bring the pins 26 substantially into the position shown in Fig. 3. This same energization of the electromagnet 19 causes attraction of its corresponding element 27 to thereby cause the cam 30 to enter between adjacent pins 26 so as to accurately center this armature and to hold the same during the time that the electromagnet 19 is energized. We might also add that the energization of one electromagnet is preferably not released until the succeeding electromagnet has been energized. After the energization of the electromagnet 19 the electromagnet 18 would be energized and immediately the energization of the electromagnet 18 takes place, electromagnet 19 is deenergized, thereby permitting electromagnet 18 to rotate the armature clockwise, which thereupon moves the element 27 related to the electromagnet 19 out of the path of the pins 26 and permits the element 27 associated with the electromagnet 18 to come into play, to thereby again cause a proper centering or graduation of the armature position. Subsequently to this, of course, the electromagnet 17 would be energized and the same functions would be performed by the element 27 corresponding to that particular electromagnet. Between the plates 15 and 16 suitable strips 31 are provided which carry binding posts 32 and 33 by means of which the current is led to the particular electromagnets.

In Fig. 5 we show the electromagnets 17, 18 and 19 as receiving their energization from a source of current 34 through the interposition of stationary switch elements 35, 36 and 37 over which a movable switch element 38 is movable. This movable switch element may be suitably controlled from any moving body, in this instance shown as a clock 39, the connection being the clock 39 and the movable switch element 38, being diagrammatically indicated by the connecting shaft 40.

In Fig. 4 we show more in detail how the

binding posts 32 are mounted so as to be insulated from their particular mounting strips 31.

Having thus described one form which 5 our invention may take, we do not wish to be understood as limiting our invention to this particular arrangement as set forth, but

Having thus described a manner in which 10 the same may be carried out, what we claim as new and desire to secure by Letters Patent is:

1. In a device of the character described the combination with a plurality of electromagnets symmetrically arranged about an axis, an armature rotatable about said axis adapted for successive movements in response to energizations of said electromagnets, and means under the control of 15 said electromagnets to cause the proper angular alinement of said armature, said means including a pivoted armature for each electromagnet and means whereby said second armatures control said first aforesaid armature.

2. In a device of the character described the combination with a plurality of electromagnets symmetrically arranged about an axis, an armature rotatable about said axis 20 adapted for successive movements in response to energizations of said electromagnets, and means under the control of said electromagnets to cause the proper angular alinement of said armature, said means including a pivoted armature for each electromagnet and means whereby said second armatures control said first aforesaid armature, said last aforesaid means including a plurality of pins upon said first aforesaid armature, and a cam upon each of said second aforesaid armatures.

3. In a device of the character described the combination with a plurality of electromagnets symmetrically arranged about an axis, an armature rotatable about said axis 45 adapted for step-by-step movement in response to different energizations of said electromagnets, and means controlled by said electromagnets and in inductive relation thereto to mechanically center said armature in each of its resting positions.

4. In a device of the character described the combination with a plurality of electromagnets, an armature adapted for step-by-step 50 movement in response to different energizations of said electro-magnets, and means controlled by said electro-magnets and in inductive relation thereto to mechanically center said armature in each of its resting positions.

5. In a device of the character described the combination with a plurality of electromagnets, an armature adapted for step-by-step movement in response to different energizations 55 of said electro-magnets, and

means controlled by said electro-magnets and in inductive relation thereto to mechanically center said armature in each of its resting positions, said means including an armature.

6. In a device of the character described the combination with a plurality of electromagnets, an armature adapted for step-by-step movement in response to different energizations of said electro-magnets, and 70 means controlled by said electro-magnets and in inductive relation thereto to mechanically center said armature in each of its resting positions, said means including an armature, a cam and pins on said first 80 aforesaid armature.

7. In a device of the character described the combination with a plurality of electromagnets adapted for energization in rotation, and an armature movable step-by-step 75 with changes in the energization of said electro-magnets, said armature consisting of a circular disk of magnetic material with unbroken periphery and having radial slots.

8. In a device of the character described 90 the combination with a plurality of electromagnets adapted for energization in rotation, and an armature having pole pieces considerably in excess of the number of electro-magnets aforesaid and being movable step-by-step with changes in the energization 95 of said electro-magnets, said armature consisting of a circular disk of magnetic material with unbroken periphery and having radial slots to form said pole pieces.

9. In a device of the character described the combination with a plurality of electromagnets adapted for energization in rotation, and an armature having pole pieces considerably in excess of the number of 105 electro-magnets aforesaid and being movable step-by-step with changes in the energization of said electro-magnets, said armature consisting of a circular disk of magnetic material having radial slots to form 110 said pole pieces.

10. In a device of the character described the combination with a plurality of parallelly arranged electro-magnets adapted for energization in rotation, and two armatures 115 coöperating respectively with the opposite extremities of said electro-magnets, movable step-by-step with changes in the energization of said electro-magnets, said armatures consisting of circular disks of magnetic material with unbroken periphery and having radial slots.

11. In a device of the character described the combination with a plurality of parallelly arranged electromagnets adapted for 125 energization in rotation, two armatures co-operating respectively with the opposite extremities of said electromagnets, movable step-by-step with changes in the energization of said electromagnets, each of said 130

armatures consisting of a circular disk of magnetic material with unbroken periphery and having radial slots, a casing for containing said electromagnets and armatures, and a partition within said casing on which said electromagnets and armatures are mounted.

12. In a device of the character described the combination with a plurality of parallelly arranged electromagnets adapted for energization in rotation, two armatures cooperating respectively with the opposite extremities of said electromagnets, movable step-by-step with changes in the energization of said electromagnets, said armatures consisting of a circular disk of magnetic

material with unbroken periphery and having radial slots, a casing for containing said electromagnets and armatures, a partition within said casing on which said electromagnets and armatures are mounted, and a plurality of indicating hands driven by said armature. 20

In witness whereof, we hereunto subscribe our names this 13th day of January, 25 A. D., 1913.

WILLIAM F. STRAUB.
ALBERT A. RADTKE.
